CONTROL MECHANISM FOR EMPTY AND
LOAD BRAKES

William E. Wine, Toledo, Ohio

Application October 18, 1935, Serial No. 45,668

14 Claims. (Cl. 188—195)

My invention relates to railway cars, more particularly to mechanism for varying the braking power of the fluid pressure brake systems of railway cars in accordance with variations in 5 the condition of loading of the car.

The principal object of the invention is to provide simple and reliable means which may be easily applied to railway cars of all types for cooperating with mechanism controlling the operation of apparatus capable of varying the braking power of the brake system.

A primary feature of the invention consists in associating with a device, which is mounted to one side of the center sill of the car for controlling the operation of apparatus for varying the braking power of the brake system, means operable by the device and extending into the center sill for cooperating with means capable of indicating the condition of loading of the 20 car.

Another feature of the invention consists in providing in combination with a device having a member movable different distances for controlling the operation of apparatus for varying 25 the braking power, means limiting the extent of movement of said member in accordance with the light or loaded condition of the car which includes a lever movable by the member and also movable independently thereof for determining the distance the lever may be moved 30 thereby.

Other features of the invention, residing in advantageous forms, combinations and relations of parts, will hereinafter appear and be pointed 35 out in the claims.

In the drawings:—

Figure 1 is a transverse vertical section view of a railway car showing the invention applied thereto.

Figure 2 is an enlarged plan view of the center sill and adjoining parts of the car adjacent one of the truck bolsters of the car.

Figure 3 is a sectional view taken on line 3—3 of Figure 2.

Figure 4 is an enlarged detail sectional view taken on line 4—4 of Figure 2.

Figure 5 is an enlarged view of the construction adjacent the central part of Figure 1.

Figure 6 is an enlarged plan view of the outer end of the operating lever and the adjacent part of the movable member of the control device.

Figure 7 is a view, partly in side elevation and partly in section, of the operating lever.

Figure 8 is a vertical sectional view illustrating a modified center construction of the car.

Figure 9 is a diagrammatic view of the apparatus for varying the braking power of the system and the device for controlling the operation of the apparatus, the various parts being

shown in their normal positions which correspond approximately to the positions they occupy when the car is loaded.

The apparatus for varying the braking power of the fluid pressure brake system of the car 5 may be of any suitable construction, the one shown in the drawings being of the type whereby the braking power is varied by changing the lever ratio of the brake rigging of the car. 10 This particular apparatus is described and claimed in my copending application Serial No. 45,665, filed October 18, 1935 and it includes a fluid pressure operating cylinder 1 and a distributing valve mechanism 2 having a slide valve 15 3 for controlling the passage of fluid pressure through a pipe 4 to the operating cylinder. The distributing valve mechanism may receive fluid pressure through a pipe 5 from any suitable source, such as the train pipe (not shown) of the fluid pressure brake system of the car. The 20 operating cylinder has a rod 6 and a guide sleeve 7, both of which are connected at their inner ends to an expandable and retractable bellows 8, a spring 9 encircling the guide sleeve being provided to maintain the rod and sleeve in their 25 innermost position within the cylinder.

The operating cylinder is adapted to actuate mechanism of the type disclosed and claimed in my copending application Serial No. 8,372, filed February 26, 1935, for varying the leverage ratio 30 of the brake rigging (not shown) of the car. This mechanism includes a brake lever formed of two pivotally connected sections 10 and 11 and a member 12 adapted to be actuated by the operating cylinder to assume a position restraining 35 movement of section 10 of the lever. The outer end of member 12, which is cooperable with lever section 10, is movably connected by a pair of links 13 to a bracket 14 rigidly mounted on a convenient portion of the car and the inner 40 end of member 12 is movably connected to the piston rod 7 by a bell crank lever 15, which may be suitably journaled on bracket 14. When there is no fluid pressure in the operating cylinder, member 12 is disposed in a position (see Figure 9) in which it is incapable of restraining movement of lever section 10 and the two sections of the lever are, therefore, capable of being moved by the brake cylinder 16 as a substantial 45 rigid unit, but, when fluid pressure is admitted into the operating cylinder, member 12 is caused to assume a position restraining movement of section 10 and accordingly only section 11 may be moved by the brake cylinder. It will thus be evident that the operating cylinder 1 functions 50 by varying the leverage ratio of the brake rigging, to vary the braking power of the brake system.

Slide valve 3, which is provided with a diaphragm 17 constantly subject to the fluid pres- 60

sure within the distributing valve mechanism, is normally prevented from assuming a position enabling fluid pressure to flow through pipe 4 to the operating cylinder by a slide bolt or the like 5 18, which is disposed in the path of movement of the stem 19 of the valve. Bolt 18 is formed with an aperture 20, which, when the bolt is actuated by fluid pressure acting on a diaphragm 21 secured to the bolt, is adapted to receive the stem 19 and thus enable the valve 3 to assume a position permitting fluid pressure to flow into the operating cylinder.

To control the operation of bolt 18 and consequently the apparatus for varying the braking power of the brake system, a device 22 is provided. 15 This device includes a fluid pressure operated member 23 which is slidably mounted within casing 24 adapted to receive fluid pressure through a pipe 25 from the distributing valve device 2. A slide valve 26 in the distributing valve mechanism controls the passage of fluid pressure to the control device 22 and, in order that fluid pressure will only flow into the control device during the interval the pressure in the distributing 20 valve mechanism is building up from a low or uncharged condition to a predetermined value, a spring 27 is associated with valve 26 for maintaining it in open position. When the pressure reaches the predetermined value, for example thirty pounds, the spring is rendered 25 inoperative and the slide valve is moved by diaphragm 28 into a position establishing communication between pipe 25 and an atmospheric port 29, whereby fluid pressure within the control device is exhausted and member 23 is returned to its normal position by spring 30. The exhaust port 29 may, if desired, be provided with a pipe 29a in open communication with the atmosphere.

The inner end of member 23 is provided with 40 two shoulders or abutments 31 and 32, respectively, spaced longitudinally thereof, between which is mounted a relatively movable slide valve 33 for controlling the passage of fluid pressure from the control device through a pipe 34 to a chamber 35, 45 in which the diaphragm 21 of bolt 18 is disposed. Slide valve 33 is normally disposed in a position, see Figure 9, in which, by means of a cavity 36 formed therein, it establishes communication of pipe 34 with an atmospheric port 37, but it is 50 capable of being moved by shoulder 31 of member 23 into a position establishing communication between pipe 34 and the interior of casing 24, so that fluid pressure may pass from the casing into chamber 35 for actuating bolt 18. It 55 will be evident that, if due to some mechanism co-operable with movable member 23, the latter is prevented from moving sufficiently to cause slide valve 33 to uncover the port communicating with pipe 34, fluid pressure will not pass from the control device into chamber 35 and fluid pressure will, therefore, not be admitted into operating cylinder 1 but, if the movable member is permitted to move sufficiently far to enable fluid pressure to pass into chamber 35, slide valve 3 will be 60 actuated to let fluid pressure flow into operating cylinder and thus actuate the mechanism for varying the leverage ratio of the brake rigging. Operation of the apparatus for varying the braking power of the brake system depends, therefore, 65 upon the extent member 23 of the control device moves.

The present invention relates to mechanism which is capable of controlling the extent of movement of member 23 in accordance with the 70 light or loaded condition of the car, that is to say,

the condition of loading of the car, to the end that, when the car is empty or nearly so, the braking power of the brake system will be less than when the car is fully loaded or substantially so. In the embodiment of the invention illustrated in the drawings, this mechanism comprises an element 38 which is movable relatively to one of the truck bolsters of the car preferably in a line substantially coincident with the pivotal axis of the truck. 10

The car truck illustrated in the drawings is of conventional design and includes a bolster 39 and side frames 40, respectively having spring units 41 upon which the outer ends of the bolster are supported. 15

As is customary, the central portion of the top wall of the truck bolster is formed so as to receive a center plate 42 secured to the under side of the car center sill 43, which may be conveniently formed as a unitary structure with a top 20 wall 44 and side walls 45.

Adjacent the truck bolster, the center sill is provided with a reinforcing casting having a cylindrical portion 47 for receiving means pivotally connecting the truck to the car. 25

In the embodiment of the invention illustrated in Figures 1 to 7, inclusive, the means pivotally connecting the truck to the car comprises the element 38 which, in effect, forms the center or king pin and extends downwardly into a cylindrical portion 48 in the bolster. The lower portion of the center pin or element 38 is bored, as at 49, to receive a pin 50 which extends downwardly through an opening 51 in the bottom wall of the bolster. Intermediate its ends, the pin is provided with a shoulder or the like 52 engaging the lower end of element 38 and interposed between the shoulder and the bottom wall of the bolster, preferably surrounding the pin, is a spring 53 for yieldingly supporting the center pin in an elevated position. 40

To facilitate assembly of the pin 50 and element 38 with the truck bolster, the opening 51 in the bottom wall of the bolster through which the pin extends is preferably formed in a removable sleeve or collar 54 having an annular flange or the like 55 resting upon the upper surface of the bottom wall of the bolster. 45

Disposed beneath the truck bolster and in the path of movement of pin 50 is means for arresting downward movement of element 38. This means is connected to an unsprung part of the car, such as the side frames of the car truck and includes side angle bars 56 connected slightly inwardly of their ends by angle bars 57 and intermediate their ends in the path of movement of pin 50 by a plate or bar 58. The end angle bars may be conveniently connected to lateral projections 59 of the spring seat portions of the side frames by any suitable means, such as pins 60. 60

As the plate 58 is carried by an unsprung part of the car and pin 50 and the element 38, which is carried thereby, are supported upon a sprung portion of the car, namely, the truck bolster, it will be evident that the space between plate 58 and the lower end of pin 50 will vary in accordance with variations in the load of the car. As less distance will intervene between plate 58 and the lower end of pin 50, when the car is loaded than when the car is empty, element 38 can not be moved downwardly as far when the car is loaded as when it is empty. The distance that element 38 is movable, therefore, reflects the condition of loading of the car. 70

The control device 22 is mounted to one side 75

of the center sill of the car and it may be advantageously secured to the center sill by an angle-shaped bracket 61 in such a position that the member 23 thereof will, under the influence 5 of fluid pressure, move upwardly in a substantially vertical direction.

Operatively interposed between element 38 and member 23 of the control device is a pivoted lever 62 having laterally offset oppositely projecting 10 arms 63 and 64. Arm 63 is disposed within the center sill and is adapted to cooperate with element 38 by engaging the upper end thereof and arm 64 is disposed exteriorly of the center sill for 15 cooperating with the upper end of movable member 23. The lever is preferably pivotally mounted 20 in one of the side walls of the center sill and, so that it may be easily associated therewith, the arms thereof are separately formed and each is provided with a reduced hub portion 65 journaled 25 within a cylindrical boss or the like 66 which may be conveniently formed integrally with the center casting 46. The inner end of the hub portion of one of the arms is provided with a recess for receiving a lug 67 formed on the inner end 30 of the hub portion of the other arm whereby the arms are keyed against relative rotation and each of the hub portions is provided with a bore for receiving a rivet or the like 68 by which the arms are securely connected together.

The outer end of arm 64 is bifurcated to provide laterally spaced portions 69 which are disposed on opposite sides of an adjustable extension 70 of movable member 23 of the control device. Inwardly of its outer end, extension 70 is formed 35 with a shoulder or the like 71 with which downwardly extending projections 72 of the bifurcated portion 69 of the arm are normally in engagement and the under sides of these projections are preferably rounded so as to have rocking engagement 40 with the shoulder. The inner end of the extension is screw threaded into the outer end of member 23, whereby shoulder 71 may be so positioned that, when the car is unloaded or contains only a small quantity of lading, the distance between 45 the lower end of pin 50 and the plate 58 will be such that the pin, upon being actuated by element 38, lever 62 and the control device, will engage plate 58 when member 23 has moved sufficiently to cause slide valve 33 to uncover the port communicating with pipe 34. It will be evident that, 50 if, when the car is unloaded or substantially so, movement of member 23 is arrested before moving far enough to cause slide valve 33 to uncover the port communicating with pipe 34, extension 70 may be adjusted to lower shoulder 71 and thus 55 increase the distance member 23 may be moved before being arrested. On the other hand, if, when the car is empty or substantially so, the distance between the lower end of pin 50 and plate 58 is so great that the pin cannot be moved sufficiently far by member 23 to cause it to engage the plate, extension 70 may be adjusted to 60 raise shoulder 71 and thus decrease the distance between pin 50 and plate 58 to such an extent that, when member 23 has moved sufficiently to 65 cause slide valve 33 to uncover the port communicating with pipe 38, pin 50 will be in engagement with plate 58.

To facilitate the proper adjustment of extension 70, lever 62 is so associated with movable member 23 as to have limited relative movement with respect thereto. To this end, the bifurcated portions 69 of the lever are formed at the lower 70 ends of projections 72 with inwardly extending lugs 73, which, when the lever is moved independ-

ently of member 23 to actuate element 38 and pin 50, are adapted to engage the under side of a head 74 formed on the outer end of the extension. The distance between the upper surfaces of lugs 73 and the under side of head 74 is substantially equal to the distance member 23 must move in order to cause slide valve 33 to uncover the port communicating with pipe 34. The lever may, therefore, only be moved independently of member 23 an amount equal to the amount member 23 must move to uncover the port leading to pipe 34.

The lever may be conveniently formed with a handle or the like 75 which may advantageously be formed as a prolongation of one of the bifurcated portions 69, so that it may be easily operated independently of the control device.

In effecting the adjustment of extension 70, which is preferably only done when the car is empty, lever 62 is manually operated. If, upon being so operated, it is found that, when the lugs 73 engage the under side of head 74, pin 50 is not in engagement with plate 58, extension 70 should be adjusted to move head 74 upwardly to enable the lever to be moved a sufficient distance to bring pin 50 into engagement with plate 58. On the other hand, if, when the lever is manually operated, pin 50 engages plate 58 before lug 73 engages the under side of head 74, extension 70 should be adjusted so as to move the head downwardly into engagement with the lugs.

To securely lock extension 70 in the desired position of adjustment, the upper end of member 23 is split longitudinally for a short distance and, at opposite sides of the split, the member is formed with lugs 76 having registering openings for receiving a bolt or the like whereby extension 70 will be firmly gripped. Furthermore, in order that the extension may be easily rotated in effecting its adjustment, the shoulder 70 may be conveniently of hexagonal shape to receive a suitable tool. To prevent element 38 and lever 62 from vibrating while the car is in transit, spring 53 is normally in compression and it, therefore, serves to maintain the lever 62 in engagement 45 with shoulder 71 of movable member 23.

Instead of employing a movable center pin, such as the element 38 for cooperating with lever 62, a construction such as that illustrated in Figure 8 may be used wherein a center pin 77 having a longitudinal bore is shown. Slidably mounted within the bore is an element 78 having a head 79 at its upper end adapted to cooperate with lever 62 (not shown in Figure 8) in the same manner that element 38 is cooperable therewith. Engaging the lower end of element 68 is a pin 80, the upper end of which is enlarged to provide a shoulder 81 and it extends upwardly through an opening formed in a wall 82, constituting a support for the center pin 77. The lower end of pin 80 projects through an opening formed in a collar 83 removably mounted within an opening in the bottom wall of the truck bolster.

Element 78 is yieldingly supported in an elevated position by a spring 84 interposed between collar 83 and a follower member 85 which is engaged by shoulder 81 of pin 80.

From the foregoing, those skilled in the art will appreciate that the mechanism for cooperating with the control device to limit movement of member 23 thereof in accordance with the condition of loading of the car is of such design that it may be easily applied to existing cars without making substantial alterations in the construc-

tion thereof and that it enables the control device to be located in an accessible place not requiring modification of the car construction and where it will be protected from injury.

5. What I claim is:

1. In a railway car having a fluid pressure brake system provided with apparatus for varying the braking power of the system according to the light or loaded condition of the car, the combination 10 with a pivoted truck having a spring supported bolster, of a center sill having substantially vertical side walls, a device mounted adjacent the center sill having a member movable different distances for controlling the operation of said apparatus, and mechanism for controlling the extent of movement of said member in accordance with the condition of loading of the car, said mechanism including an element movable with respect to the truck bolster in a line substantially coincident with the pivotal axis of the truck, said element having a portion disposed within the center sill, and means engageable with said member and having a portion extending through one of the side walls of the center sill for cooperating with 20 said element.

2. In a railway car having a fluid pressure brake system provided with apparatus for varying the braking power of the system according to the light or loaded condition of the car, the combination 30 with a pivoted truck having a spring supported bolster, of a center sill, a device mounted adjacent the center sill having a member spaced to one side of the pivotal axis of the truck and movable different distances for controlling the operation of said apparatus, and mechanism for controlling the extent of movement of said member in accordance with the condition of loading of the car, said mechanism including an element relatively movable with respect to the truck bolster and having a portion disposed within the center sill, and means cooperable with said portion of the element and having a portion disposed exteriorly of the center sill engageable with said member.

3. In a railway car having a fluid pressure brake system provided with apparatus for varying the braking power of the system according to the light or loaded condition of the car, the combination 40 with a pivoted truck having a spring supported bolster, of a center sill, a device mounted adjacent the center sill having a member movable different distances for controlling the operation of said apparatus, and mechanism for controlling the extent of movement of said member in accordance with the condition of loading of the car, said mechanism including an element relatively movable with respect to the truck bolster in a line substantially coincident with the pivotal axis of the truck and a lever pivotally mounted on the center sill having a portion engageable with said member and a portion cooperable with said element.

4. In a railway car having a fluid pressure brake system provided with apparatus for varying the braking power of the system according to the light or loaded condition of the car, the combination 50 with a pivoted truck having a spring supported bolster, of a center sill, a device mounted to one side of the center sill having a member movable different distances for controlling the operation of said apparatus, and mechanism for controlling the extent of movement of said member in accordance with the condition of loading of the car, said mechanism including an element relatively movable with respect to the truck bolster and having a portion disposed within the center sill, and

means pivotally mounted on the center sill having a plurality of arms, one of said arms being disposed exteriorly of the center sill and being engageable with said member and the other of said arms being disposed interiorly of the center sill and being cooperable with said element. 5

5. In a railway car having a fluid pressure brake system provided with apparatus for varying the braking power of the system according to the light or loaded condition of the car, the combination 10 with a pivoted truck having a spring supported bolster, of a center sill, a device mounted to one side of the center sill having a member movable different distances for controlling the operation of said apparatus, and mechanism for controlling the extent of movement of said member in accordance with the condition of loading of the car, said mechanism including an element relatively movable with respect to the truck bolster and having a portion disposed within the center sill, and means journaled in one of the side walls of the center sill having laterally spaced oppositely projecting arms, one of said arms being engageable with said member and the other of said arms being cooperable with the said portion of said element. 15

6. In a railway car having a fluid pressure brake system provided with apparatus for varying the braking power of the system according to the light or loaded condition of the car, the combination with a pivoted truck having a spring supported bolster, of a center sill, a device mounted to one side of the center sill having a member movable different distances for controlling the operation of said apparatus, and mechanism for controlling the extent of movement of said member in accordance with the condition of loading of the car, said mechanism including an element vertically slidably in a line substantially coincident with the pivotal axis of the truck, spring means for maintaining said element in an elevated position, pivoted means actuated by said member having a portion extending into the center sill for moving said element downwardly, and means connected to an unsprung part of the car affording a stop limiting downward movement of said element. 30

7. In a railway car having a fluid pressure brake system provided with apparatus for varying the braking power of the system according to the light or loaded condition of the car, the combination 35

with a pivoted truck having a spring supported bolster, of a center sill, a device mounted adjacent the center sill having a member movable different distances for controlling the operation of said apparatus, and mechanism for controlling the extent of movement of said member in accordance with the condition of loading of the car, said mechanism including a vertically slidably element extending within the center sill, spring means for maintaining said element in an elevated position, stop means connected to an unsprung part of the car limiting downward movement of said element, and a pivoted lever operable by said member for moving said element downwardly, said lever being movable independently of said member for manually actuating said element, said member having means movable therewith affording a stop limiting the extent said lever is movable independently of said member. 40

8. In a railway car having a fluid pressure brake system provided with apparatus for varying the braking power of the system according to the light or loaded condition of the car, the combination with a pivoted truck having a spring 45

supported bolster, of a center sill, a device mounted adjacent the center sill having a member movable different distances for controlling the operation of said apparatus, and mechanism for controlling the extent of movement of said member in accordance with the condition of loading of the car, said mechanism including a vertically slideable element extending into the center sill, spring means for maintaining said element in an elevated position, stop means limiting downward movement of said element, and a pivoted lever operable by said member for moving said element downwardly, said lever being movable independently of said member for manually actuating said element and said member having a portion provided with spaced shoulders limiting the extent of movement of the lever independently of said member, said lever being normally in engagement with one of said shoulders for operation by said member and said portion being adjustable longitudinally of the member to position the other one of said shoulders so that, when the lever is moved independently of the member and the car is in a predetermined condition of loading, said lever will engage said last named shoulder at substantially the same time said element engages said stop means.

9. In a railway car having a fluid pressure brake system provided with apparatus for varying the braking power of the system according to the light or loaded condition of the car, the combination with a pivoted truck having a spring supported bolster, of a center sill, a device mounted adjacent the center sill having a member movable different distances for controlling the operation of said apparatus, and mechanism for controlling the extent of movement of said member in accordance with the condition of loading of the car, said mechanism including a vertically slideable element extending into the center sill, and a lever operable by said member actuating said element, said lever and member having a lost motion connection permitting movement of said element independently of said member for manually operating said lever.

10. In a railway car having a fluid pressure brake system provided with apparatus for varying the braking power of the system according to the light or loaded condition of the car, the combination with a pivoted truck having a spring supported bolster, of a center sill, a device mounted to one side of the center sill having a member movable different distances for controlling the operation of said apparatus, and mechanism for controlling the extent of movement of said member in accordance with the condition of loading of the car, said mechanism including a vertically slideable element extending into the center sill, spring means normally maintaining said element in an elevated position, stop means connected to an unsprung part of the car for limiting downward movement of said element, and a lever operable by said member for moving said element downwardly, said lever being movable independently of said member and being provided with an extension affording a handle whereby said lever may be manually operated for actuating said element independently of said member.

11. In a railway car having a fluid pressure brake system provided with apparatus for varying the braking power of the system according to the light or loaded condition of the car,

the combination with a pivoted truck having a spring supported bolster, of a center sill, a device mounted to one side of the center sill having a member movable different distances for controlling the operation of said apparatus, and mechanism for controlling the extent of movement of said member in accordance with the condition of loading of the car, said mechanism including an element relatively movable with respect to the truck bolster, stop means limiting relative movement of said element and truck bolster in one direction, and a pivoted lever movable by said member and cooperable with said element, said lever being normally in engagement with said member and being movable independently thereof to determine the distance said lever is movable by said member.

12. In a railway car having a fluid pressure brake system provided with apparatus for varying the braking power of the system according to the light or loaded condition of the car, the combination with a pivoted truck having a spring supported bolster, of a device having a member spaced to one side of the pivotal axis of the truck and movable different distances for controlling the operation of said apparatus, and mechanism for controlling the extent of movement of said member in accordance with the condition of loading of the car, said mechanism including an element movable with respect to the truck bolster in a line substantially coincident with the pivotal axis of the truck, and movable means operatively interposed between said member and said element.

13. In a railway car having a fluid pressure brake system provided with apparatus for varying the braking power of the system according to the light or loaded condition of the car, the combination with a pivoted truck having a spring supported bolster, of a device having a member spaced to one side of the pivotal axis of the truck and movable different distances for controlling the operation of said apparatus, and mechanism for controlling the extent of movement of said member in accordance with the condition of loading of the car, said mechanism including means movable with respect to the truck bolster in a line substantially coincident with the pivotal axis of the truck, and pivoted means operatively interposed between said movable means and said element.

14. In a railway car having a fluid pressure brake system provided with apparatus for varying the braking power of the system according to the light or loaded condition of the car, the combination with a pivoted truck having a spring supported bolster, of a device having a member spaced to one side of the pivotal axis of the truck and movable different distances for controlling the operation of said apparatus, and mechanism for controlling the extent of movement of said member in accordance with the condition of loading of the car, said mechanism including means movable with respect to the truck bolster in a line substantially coincident with the pivotal axis of the truck, and means having a portion extending at an angle to the pivotal axis of the truck operatively connecting said movable means and said element.
